UNITED STATES PATENT OFFICE.

CLARENCE E. LITTLE, OF LYNN, MASSACHUSETTS, ASSIGNOR TO GENERAL ELECTRIC COMPANY, A CORPORATION OF NEW YORK.

MEANS FOR SECURING BUCKETS IN TURBINES.

No. 841,258.

Specification of Letters Patent.

Patented Jan. 15, 1907.

Application filed July 19, 1905. Serial No. 270,432.

To all whom it may concern:

Be it known that I, CLARENCE E. LITTLE, a citizen of the United States, residing at Lynn, county of Essex, State of Massachusetts, have invented certain new and useful Improvements in Means for Securing Buckets in Elastic-Fluid Turbines, of which the following is a specification.

The present invention has for its object to improve and simplify the means for attaching buckets to their supports whereby the machine is more readily assembled and taken down, the alinement of the parts rendered more certain, and the cost of manufacture reduced.

In the accompanying drawings, which illustrate one embodiment of my invention, Figure 1 is an axial section of a turbine with the governor-casing in elevation, the section being taken on line 1.1 of Fig. 2. Fig. 2 is a cross-section of the same with certain of the parts in elevation. Fig. 3 is a perspective view of one of the attaching-bolts, and Fig. 4 shows a detail section wherein three rows of intermediates are provided.

The casing 1 is preferably made as a single casting to eliminate the joints as far as possible. It can, however, be made in two or more parts, if desired. When the latter arrangement is followed, the parts will ordinarily be fastened together once for all, since the wheel and the intermediate buckets are made removable by a relative axial movement of the wheel and casing. The right-hand end 2, or the bottom, in the case of a vertical-shaft machine, is preferably, but not necessarily, formed integral with the casing, while the left-hand end or head 3, or the top, in case of a vertical-shaft machine, is made removable and is secured in place by suitable means, such as bolts. At the points of entrance to the casing the shaft 4 or hub 5 of the bucket-wheel is provided with packings 6 and 7 to prevent the escape of motive fluid.

The wheel is provided with two or more rows of buckets 8 to produce rotation when subjected to elastic fluid under velocity from the nozzle or other fluid-discharging device 9. The nozzle is preferably of the expanding type and converts the pressure of the fluid wholly or largely into velocity before discharging it to the wheel. The nozzle is usually of the sectionalized type, comprising a number of closely-associated passages which

discharge the motive fluid in the form of a solid column or jet. Between each two rows of wheel-buckets are more or less complete rows of intermediate buckets 10, which serve to reverse the motive fluid as it flows through one row of buckets after the other and has its velocity abstracted by successive operations. These intermediate buckets are provided with sharp edges and are closely associated, so that the motive fluid is discharged as nearly as possible in a solid column. When these intermediate buckets cover less than the entire circumference of the wheel, blank walls 11 are provided, which extend from one end of the bucket support or ring to the other or from one set of buckets to the other, as the case may be. These blank walls are finished on the sides and are separated from the wheel-buckets by axial clearances, which are substantially the same as the clearances between the wheel and intermediate buckets. When the parts are thus arranged, the walls assist in reducing rotation losses by preventing the fan-like action of the idle moving buckets. The right-hand wall of the casing and also the head are shaped to conform to the wheel to further reduce rotation losses.

The interior of the wheel-casing is provided with a shoulder 12, that may be integral with or attached to the casing. Abutting this shoulder is a ring carrying the intermediate buckets when the latter extend entirely around the wheel and the intermediates and blank walls when the former extend only partially around the wheel. This ring may be made in two or more pieces. The buckets may be cut or cast therein. The periphery of the ring makes a working fit with the casing, or some part thereof, which serves to center it and also to hold it in place. The entire inner surface of the casing need not be finished on account of expense, but should at least be finished in spots or provided with projections which are finished. The main thing is to center the rings properly, so that the alinement of the buckets will be preserved at all times, and to guide them when being inserted in place. However the inside of the casing is finished the rings should be arranged to slip freely into the casing one after the other. Adjacent to the ring above referred to is a follower 13, comprising a ring which may be made in one or more pieces. The periphery is finished and engages some

part or parts of the casing, which serve to center it. The opposite sides of the ring are carefully finished, so that it serves as a spacing device for separating one intermediate-bucket ring from the other. In addition to this the follower-ring serves to decrease the rotation losses of the rapidly-revolving wheel, and it also cuts down the free space in which the exhaust fluid can collect. On the side of the follower adjacent the inlet is a second ring having a row of intermediates 14 and blank walls 15 of the same construction, as previously described. In most cases the number of intermediates and the number of active wheel-buckets will be less at the high-pressure end of the machine and gradually increase in number toward the exhaust. The cross-sectional area of the bucket-spaces will also increase toward the exhaust.

As before explained, the intermediate-bucket supports and blank walls and the follower are arranged in the form of rings, which make a working fit with certain surfaces within the casing in order to be readily movable by an axial movement of the casing and wheel relatively to each other. In order to prevent these parts from moving circumferentially with respect to the casing when the machine is in operation, one or more keys 16, Fig. 2, or equivalent devices are employed, which are common to said parts. This arrangement will permit the parts to be rather loosely fitted without permitting the relation to be disturbed. In order to clamp the parts in place and at the same time permit of the head being removed without disturbing them, individual clamping devices 17 are provided, of which as many are provided as are necessary. These retaining devices comprise a clamping-piece 18, which engages the first ring, and also a cylindrical shoulder 19, formed on or attached to the wheel-casing. Extending through the clamp is a bolt which enters the shoulder and is accessible from the high-pressure end of the machine when the head is removed. The bolt exerts axial pressure on the parts and is prevented from turning by a lock-washer 20, which is provided with lips 21, that engage the head of the bolt. The washer itself is prevented from turning by the projection 22, that engages a flattened portion of the cylindrical clamping-piece 18. The clamping-pieces fit into a slight depression or orifice 23, formed in the casing, and by reason of the eccentric arrangement of the clamping-bolts are prevented from turning.

In assembling the parts the casing is moved up adjacent to the wheel and the parts of the first intermediate-bucket ring placed around the wheel. Then the casing is moved along to engage the ring. The next step is to mount the follower in place and move the casing along to engage and hold it in place. The parts of the second ring are then placed around the wheel and the casing moved along

axially to engage it. The rings and follower are then moved against the seat or shoulder on the casing and the clamps mounted in place. Finally the head 3 and attached parts are mounted in place.

In event of the rings being continuous they can be applied to the wheel before the succeeding rows of buckets after the first are mounted in place. In this case the diameter of the inner surface of the rings should be slightly greater than the diameter of the portion or portions of the wheel over which they must slide, as will be readily understood.

In Fig. 4 are shown three rings composed of intermediate buckets and blank walls, and two followers situated between the adjacent rings. The number of bucket-rings and followers can be increased *ad libitum*, since it in no way changes the principle of my invention.

In so far as the idea of using rings, either complete or segmental, is concerned the blank portions or walls between the buckets need not act as devices for decreasing rotation losses; but I consider it advisable to use them.

The invention is applicable to vertical-shaft machines and also to multistage machines whether the shaft be vertical or horizontal.

The governor for controlling the speed of the turbine is mounted on the end of the shaft and is inclosed by the casing 24. Steam or other elastic fluid is admitted to the nozzle or nozzles from a suitable valve-chest 25. The exhaust from the wheel is discharged into a circular conduit 26, that is connected to a suitable point of exhaust—such, for example, as the atmosphere or a condenser.

In some instances the head may be provided with one or more projections, movable or otherwise, which engage the adjacent ring, and thus hold the parts in place. When such an arrangement is employed, the bolts retaining the cover will also serve to hold the parts in place. It is the better practice to have one or more clamps which are movable independently of the head to hold the parts, since by so doing the effects of errors in machine-work are reduced to a minimum.

In accordance with the provisions of the patent statutes I have described the principle of operation of my invention, together with the apparatus which I now consider to represent the best embodiment thereof; but I desire to have it understood that the apparatus shown is only illustrative and that the invention can be carried out by other means.

What I claim as new, and desire to secure by Letters Patent of the United States, is—

1. An elastic-fluid turbine comprising a wheel having rows of peripheral buckets, a casing, and fluid-admitting means, in combination with closely-associated intermediate buckets, a support therefor located between

the rows of wheel-buckets and conforming to the shape of the casing, a blank wall connecting the ends of the intermediate-bucket support, a shoulder for positioning the intermediate buckets within the casing, and a clamping device for the support which exerts pressure in an axial direction.

2. An elastic-fluid turbine comprising a wheel having rows of buckets thereon, a fluid-admitting means, and a casing, the wheel and casing being so arranged that they can be separated by an axial movement, in combination with closely-associated intermediate buckets arranged in segmental rows, supports therefor located between the rows of wheel-buckets, blank walls connecting the opposite ends of the segmental rows of buckets, a follower or spacer between the rows of intermediate buckets, and one or more devices for exerting pressure in an axial direction on the intermediate - bucket supports and the follower or spacer.

3. An elastic-fluid turbine comprising a wheel having rows of buckets thereon, a fluid-admitting means, and a casing, in combination with two or more rows of closely-associated intermediate buckets having sharp edges and arranged in rings, portions of which are blank, a follower between each two adjacent rings, an abutment receiving one of the rings, and one or more devices which exert a pressure on the rings and the follower to seat the parts against the abutment.

35 4. An elastic-fluid turbine comprising a wheel having rows of buckets thereon, a fluid-admitting means, and a casing having a shoulder, in combination with intermediate buckets arranged in the form of rings which are slipped axially into the casing, a follower-ring between each two intermediate-bucket rings, means which engages one of the rings and said shoulder for clamping the bucket and follower rings in place, and a key for preventing the bucket and follower rings from turning.

5. In an elastic-fluid turbine, the combination of a wheel having rows of peripheral

buckets thereon, a casing having an internal shoulder, an intermediate-bucket ring which 50 rests on the shoulder, a second intermediate-bucket ring, a follower between said rings which separates them by a fixed distance, a second shoulder formed on the casing, and clamping devices which engage the second 55 shoulder and also a ring for holding the intermediate buckets in place.

6. In an elastic-fluid turbine, the combination of a wheel having rows of peripheral buckets thereon, a casing having an internal 60 shoulder, intermediate-bucket rings which are restrained from axial movement by the shoulder, a follower between the rings, clamping devices located within the casing which exert axial pressure on the rings and follower, a nozzle or other device admitting fluid to the buckets, and a head for the casing which carries the nozzle and when removed exposes the clamping devices.

7. In an elastic-fluid turbine, the combination of a casing, a wheel having rows of peripheral buckets, intermediate-bucket-carrying rings located between the rows of wheel buckets, a follower between adjacent bucket-rings, shoulders formed on the casing, one of 75 which acts as an abutment, and clamping devices which engage the other shoulder and also one of the rings.

8. In an elastic-fluid turbine, the combination of a casing, a wheel having rows of peripheral buckets, intermediate-bucket-carrying rings located between the rows of wheel buckets, which are slipped into the casing one after the other, blank walls on the rings which reduce the fan-like action of the idle- 80 wheel buckets, a follower which surrounds the wheel and spaces the adjacent rings and is slipped into the casing between the rings, and means for clamping the rings and followers in place.

In witness whereof I have hereunto set my hand this 7th day of July, 1905.

CLARENCE E. LITTLE.
